Lovell Manufacturing Company, Erie, Pa., a
corporation of Pennsylvania

Original application January 22, 1936, Serial No.
60,325. Divided and this application March 17,
1937, Serial No. 131,342

1 Claim. (Cl. 68—269)

Power wringers present a very definite problem in supplying devices that can be actuated to prevent serious injury when the operator gets her hand or fingers caught in the wringer rolls. The present invention is designed to improve wringers with relation to the safety mechanism.

This application is a division of application No. 60,325 filed January 22, 1936, in which a new form of trip mechanism forms the principal feature.

10 The present invention is directed primarily to the driving mechanism for the wringer and particularly to means by which power mechanisms may be more conveniently and sensitively controlled so that the driving of the rolls may be instantaneously stopped. Features and details of the invention will appear from the specification and claim.

Preferred embodiments of the invention are illustrated in the accompanying drawings as 20 follows:

Fig. 1 shows a section of a wringer involving the invention on the line 1—1 in Fig. 2.

Fig. 2 a front elevation of the same wringer, partly in section.

25 Fig. 3 a sectional view of the power end of the wringer and a sectional view of the gear box with the driving mechanism.

Fig. 4 a section on the line 4—4 in Fig. 5.

Fig. 5 a section on the line 5—5 in Fig. 3, the 30 gear being in neutral.

Fig. 6 a similar section showing the parts set for a driving movement of the gear mechanism.

Fig. 7 a sectional view on the line 7—7 in Fig. 8 showing a modification.

35 Fig. 8 a front elevation of the same wringer.

Fig. 9 a section of the end of the wringer shown in Figs. 7 and 8 with the gear box attached and in section.

Fig. 10 a section on the line 10—10 in Fig. 9.

40 Fig. 11 a perspective view of the reversing levers of the control mechanism.

Fig. 12 a section on the line 12—12 in Fig. 11.

The frame of the wringer is made up of the base 1, side stiles 2 and 3, and top bar 4. It has 45 the lower wringer roll 5, the upper wringer roll 6, the drive shaft 7 extending through the lower roll, the shaft 8 extending through the upper roll, bearings 9 for the shaft 7 of the lower roll, these 50 bearings being arranged in the stile, and bearings 10 slidably mounted in the side stiles in which the shaft 8 is journaled. A pressure spring 11 operates on the upper bearings and is adjusted by the usual adjusting screw 12. One end of the top bar is secured to the side stile 2 by inter-

locking shoulders 13. The opposite end is secured by a safety device being along the same lines as shown in my application, Serial Number 45,279 in which there are cross slides 14 in the top bar with actuating bars 15 along the front and back of the top bar. The slides 14 operate a rocking plate 16 swingingly mounted in the top of the top bar and having a trip end 17 adapted to engage the end of a latch 18. The latch 18 is pivoted on a pin 19. It has a hook 20 which engages under a shoulder 21 in the side stile. When the plate 16 is moved sidewise it releases the latch 18 and the latch releases the top bar and as the top bar swings up the interlocking shoulders are unhooked and the pressure on the spring is thus released.

Clothes guides 22 are secured in side brackets 23 at the front and rear of the wringer frame. These guides are directed to feed the clothes toward the bite of the rolls. A trough 24 is arranged under the rolls in position to catch the water and this is discharged from this trough through an opening 25.

A safety bar 26 is arranged in continuation of the guide forming a slight abutment at the upper 25 end of the guide. This bar is pivotally mounted on pivot rods 27 and 28 extending into the brackets 23, the rod 27 extending into the gear box to control the shifting mechanism for the gears. The inward end of the guide 22 has a depressed 30 portion 29 leading into the trough and this makes a fairly close fit with the edge of the bar 26 when the front face of the bar is swung inwardly. The bar has a downwardly extending lip 30 at its inner edge which lip is adjacent to the lower roll. By 35 exerting pressure on this bar, either toward the roll or away from the roll, the rod 27 is rocked. Thus the trip bar may be actuated by the operator when it is desired to disconnect the driving mechanism and it is automatically operated when the clothes wind around the lower roll by the engagement of the clothes with the projection 30. It also stops the power when the clothes follow down the lower roll and engage the safety bar at 40 the discharge side.

45 When the bar is operated it brings the gear mechanism to neutral and stops the roll. A preferred mechanism for this purpose is as follows: A shaft 32 is journaled in a bearing 33 in a gear box 34. The shaft 32 is connected with the shaft 50 7 by a coupling 35. A beveled gear 36 is fixed on the shaft 32 and meshes with gears 37 and 38 journaled on a drive shaft 39. A clutch member 40 is slidably mounted on the shaft 39 and splined thereon. The ends of the member 40 and 55

the faces of the gears 37 and 38 have interlocking detents and projections 41 forming clutch engaging means in the usual manner. The member 40 has an annular rib 42 and a block 43 is provided with a groove engaging the rib 42. The block 43 has a cross slot 44 in which a crank pin 45 operates. The pin 45 is carried by a disc 46 and the disc is mounted on a shaft 47. A setting handle 48 is fixed on the shaft 47. By throwing this handle the crank 45 is moved and consequently the clutch member is moved into engagement either with the upper gear, or the lower gear, thus driving the wringer in either direction. The disc has locking notches 49 which are adapted to be engaged by pins 50 arranged in a cross slide 51. The cross slide has slots 52 through which plates 53 formed in extension of the shafts 27 at the front and rear of the wringer extend. Springs 54 are secured at each side of a rock arm 55 extending from the disc 46 and yieldingly throw the sliding latch plate 51 carrying the pins 50 into locking engagement with the slots 49 as the disc is thrown through the action of the handle for setting the gears. Therefore, the gear setting is locked by the pins 50 and operates until tripped.

This setting can be easily released by a very sensitive mechanism because it is only necessary to withdraw the pin 50 from its locking position. This is accomplished in the present invention by 30 rocking the rods 27. This rocking of the rods at either side, or in either direction, swings a plate 53 and this moves the latch 51 to carry the pin 50 in engagement with the notch 49 out of such notch and thus releases the disc 46 which swings 35 to its neutral position through the action of the spring 54 which has been put under tension. This immediately brings the parts to neutral and stops the wringer. It will be understood that the interlocking portions of the clutch have their engaging surfaces slightly inclined so that this assists in the disengaging movement when the lock is tripped.

The following mechanism is provided for releasing the trip mechanism so as to bring the 45 gear mechanism to neutral from a single position. This is accomplished by providing cams 56 on the inner faces of upward projections of the slide 51. These cams are adapted to operate in connection with cams 57 on a cross head 57a. 50 A pin 58 extends upwardly from the cross head through a bearing in the gear box and terminating with a press button 59. A spring 60 yieldingly holds the rod 58 upwardly.

When it is desired to release the driving mechanism the button 59 is merely depressed and the camming action forces the latch sidewise so as to bring the pin 50 out of the locking notch and releases the mechanism.

In the modification shown in Fig. 7 and following the wringer is similar to that shown in the previous structure except that the safety device is omitted. The top bar has the interlocking shoulders 61 at one end and at the opposite end has a re-setting device comprising a lever 61 of 65 U-shape in cross section pivotally mounted on the top bar at 62. This lever 61 is pivotally connected with a link 63 by means of a pivot 65 and the link 63 is connected with the frame by a pivot 64. When the lever is thrown up the toggle 70 mechanism is released and the top bar is released. When brought down the top bar is forced down to position re-setting the pressure on the spring.

The wringer roll shafts, gear box and gear arrangement is the same as that in the preceding 75 structure and the reversing clutch is also similar.

The actuating bars for controlling the gears are, however, slightly different. Guides 66 are arranged on the front and rear of the frame. The guides have downward lips 67 which enter the trough. A trip bar 68 is arranged at the front and rear of the wringer. The bar is pivotally mounted on rods 69 and 70, the rod 69 being carried through to the gear box to actuate the setting of the gear mechanism. The bar 68 has a face 71 adapted through the camming action of the clothes on this portion of the bar to depress the bar and accomplish a tripping action. The bar 68 also has a lip 72 which is in position to be engaged by clothes wrapping on the roll, or clothes jamming at the discharge side in which event the trip bar is rocked and the gear driving mechanism thrown to neutral.

In order that the trip bar may be actuated by clothes winding on the upper roll levers 73 are arranged at each side of the wringer and engages 20 the ends of the lip 72. These levers are pivoted at 74 and have cross bars 75 extending across the upper roll in position to be engaged by the clothes if wrapped on the upper roll.

The tripping mechanism for controlling the 25 gear clutch is modified from that shown in the preceding figures and is as follows: A shaft 76 is journaled in the gear box and carries a disc 77. This disc has a crank pin 78 operating in the grooves 44 of the block operating on the clutch 30 member. The disc has an arm 79 from which a handle 80 extends, the handle extending through a slot 81 in the wall of the gear box. By operating this handle the crank can be operated and the clutch member thrown up or down to drive 35 the wringer in either direction, or may be fixed at neutral so as to disengage the driving mechanism.

An arm 82 is arranged on the disc 77 and springs 83 operate on this arm to yieldingly 40 draw the crank to neutral position when the parts are released.

Levers 84 are fixed on the shafts 69 and rock with these shafts. These levers 84 are U-shaped, the sides being connected only at the ends by a cross plate 85. The two levers are connected together at reverse ends by a link 86, the link 86 being connected to the outer strap only of the levers 84 by pivot pins 87. This link compels the pivoted levers to move together, opening the top or closing the top together. A trip plate 88 is mounted on the arm 79, its ends extending between the walls of the levers 84. Each end of the trip plate is provided with a stop shoulder 89 which is adapted to engage the end of the connecting strap 85 when the trip plate 88 is thrown in either direction through the action of the arm 79. It will be seen that when the handle is operated and the arm 79 thrown the trip plate is swung so as to bring the shoulder 89 out of the lever 84 and the springs 83 which have been put under tension snap this lever in behind the stop and lock the trip plate and consequently the arm 79 and crank in the set position. When, however, either rod 69 is rocked by a downward, or inward movement of the trip plate 88, the lever 84 is rocked so as to draw the strap 85 away from the shoulder 89 and thus release the trip bar and with it the rock arm 79 and the clutch.

A release button 90 is connected by a post 91 70 and the post 91 has a cross head 92. The ends of the cross head are slotted at 93 and pins 94 extend through these slots into the inner walls of the levers 84. By pressing down on the button 90 the cross head operating on the upper ends of 75

the levers 84 rocks them inwardly and disengages the shoulders 89, thus immediately permitting the parts, under the action of the springs, to spring to neutral. It will be seen, therefore, that the operator by exerting downward pressure, or inward pressure, on the actuating bar can stop the wringer and the operator then can, if desired, immediately reverse the wringer and disengage the hand. It will also be noted that any wrapping, or jamming of the clothes also actuates the bar and throws the driving mechanism into neutral position.

What I claim as new is:

In a wringer, the combination of a frame; rolls mounted in the frame; a driving mechanism; a driving connection between a roll and the mechanism; controlling devices controlling the connection, said devices yieldingly tending to break the connection; a trip means retaining and releasing the controlling devices; a rocking control means operating the trip means with either direction of rocking movement; and an actuator operating the rocking control means.

WALTER L. KAUFFMAN, II.
